Thomas J. Kelleher.

By Charles Turner Brown, M.D.

UNITED STATES PATENT OFFICE.

THOMAS J. KELLEHER, OF CHICAGO, ILLINOIS.

BENDING BRAKE.

Application filed April 7, 1924. Serial No. 704,715.

To all whom it may concern:

Be it known that I, THOMAS J. KELLEHER, a citizen of the United States, and a resident of Chicago, in the county of Cook and State of Illinois, have invented certain new and useful Improvements in Bending Brakes, of which the following, when taken in connection with the drawings accompanying and forming a part hereof, is a specification.

10 This invention relates to improvements in that class of machines which are used for bending and curving sheet metal and metal bars, and by means of which sheet metal of large size and of considerable thickness 15 may be bent or folded, as well as metal bars, also of considerable thickness.

Among the objects of the invention are to obtain brakes of great strength and rigidity, which are built up of a small number of 20 parts or pieces to obtain, respectively, the bed, the upper jaw, and the apron or leaf of the brake; each thereof when completed, forming an integral mass; to obtain a brake which is durable and not liable to break or 25 get out of order; and the several members thereof are not liable to be distorted when used on what is termed heavy material; to materially reduce the initial cost of bending brakes, and to obtain a bending brake which 30 is readily understood and easily operated by men skilled in the art of bending sheet and bar metal.

I obtain the objects recited by the use of different qualities or kinds, as well as of 35 different thickness, of steel in the construction; and by the means employed in joining the several elements comprised in each of the members of the brake; thereby securing the requisite strength, while obtaining a 40 reduction in the weight of the brake.

In the drawings referred to Figure 1 is a front elevation of a bending brake embodying this invention;

Fig. 2 is a rear elevation of the bending 45 brake which is illustrated in Fig. 1;

Fig. 3 is an end elevation of said bending 50 brake;

Fig. 4 is a vertical section of the forward end of the bed and movable upper jaw, and 55 the upper portion of the apron or bending leaf of the brake, on line 4-4 of Fig. 1, viewed as indicated by arrows;

Fig. 5 is a horizontal section of one end of 60 the apron, on line 5-5 of Fig. 1, viewed as indicated by arrows; and

Fig. 6 is a vertical section of a modified

construction of the lower member of the clamping jaw and of the thrust receiving bar of the apron of the brake.

A reference character applied to designate 60 a given part indicates said part throughout the several figures of the drawings wherever the same appears.

1, 2, represent the supporting legs of the 65 brake; 3 represents a horizontal base member, to which the lower ends of legs 1, 2, are secured, as by rivets 3^a, 3^a; and 4, 4, represent diagonally extending braces which are secured at their lower ends to the horizontal base members 3, 3, as by bolts or rivets 4^a, 70 4^a, and to the legs, as by bolts or rivets 4^b, 4^b, (see Figs. 2 and 3), and 4^c, 4^c. 5, 5, Figs. 1 and 3, represent heads, preferably of cast steel, to which the ends of the bed of the 75 brake are secured. Said bed is secured adjacent to its ends on the frame composed of the legs, the horizontal base members (3, 3,), and the braces 4, 4, hereinbefore described. 6 represents the bed of the brake, which is 80 preferably made of sheet steel, and 7 the lower jaw, preferably made of highly carbonized steel. The ends of the bed 6 are secured to said heads 5, 5, by rods 8, 8, which are respectively welded to said heads and to 85 said bed, (see Fig. 3). The bed 6 is secured to the upper end of the frame composed of the legs, the horizontal members 3, 3, and braces 4, 4, by rods 6^a, 6^a, Fig. 4, which are welded to the upper ends of said legs and to the under side of said bed. The lower jaw 90 7 is secured to the bed 6 by rods 9, 9, which are welded to said jaw and to said bed, (see Fig. 4). The heads 5, 5, are extended at 10, Fig. 3, to form parts of a hinge to which the part 11, forming the remainder of the hinge, and 95 supporting the hereinafter described apron or bending leaf, is pivotally joined by pintles 12. The apron or turning leaf of the brake consists of heads 13, 13, on the upper ends of which the described hinge members 11, 11, are respectively positioned, 100 said hinge members being integral with said head, and preferably made of cast steel; the metal plate member 14, preferably of sheet steel; the bending member 15, preferably 105 made of highly carbonized steel; and the curved plate 16, preferably made of sheet steel. The upper edge of plate member 14 is secured to the lower edge of the bending member 15, by the rods 17, 17, (Fig. 4) 110 which are, respectively, welded to said members 14, 15; and the ends of said members 14,

15, are secured to heads 13, 13, by rods 17^a, 17^a, which are welded to said head 13, and to said plate member 14, and said bending member 15, respectively; and the curved plate 16 is secured to bending member 15, by rods 18, 19, which are, respectively welded to said member 15 and plate 16. The forward end of the lower jaw 7 is bevelled, as at 20, Fig. 4, and the upper end or edge of member 15 is correspondingly bevelled, as at 21. The upper edge, (22) of member 15 receives the thrust when material (as 52) secured between the lower jaw 7 and the hereinafter described upper jaw, is bent; and the purpose of the bevelled edges 20, 21, is to enable me to use a greater thickness in member 15 than can otherwise be done. Where exceedingly heavy metal is to be bent, the member may be reinforced in the ordinary way by attaching a steel bar and an angle iron to the face thereof, the position of said steel bar and angle iron being indicated in Fig. 4, by broken lines 23, 24; but said bar and angle iron and the attaching thereof to the bending member of the apron which receives the thrust of bending or folding material in the operation of the brake forms no part of my invention. I find, however, that by constructing the lower jaw of highly carbonized steel and as hereinbefore recited with the forward end of member 7 bevelled as at 20, and the upper end of the thrust or bending member 15 of the apron bevelled, as at 21, while the upper edge 22 of said member 15 is parallel with the lower edge of said member, much thicker and heavier sheet and bar metal may be bent or formed by the brake, without the use of steel plate 23 and angle 24, than, so far as I am aware, can be done by any previous construction of said apron.

The upper jaw comprises the heads 25, 25, which is preferably of cast steel, the horizontal table 26, which is preferably of sheet steel; said head secured to the ends of said table by rods 27, 28; said rods being welded to said heads 25, 25 and table 26. Said upper jaw also includes the inclined plate 29, which, at its lower side is secured to the forward side or edge of table 26 by rods 30, 31, which are welded to said table 26 and inclined plate 29. The upper jaw also includes struts 32, 32, the lower ends of which are secured to table 26, by rods 34, 35, which are, respectively, welded to said table 26 and to the lower ends of said struts 32; and the upper ends of said struts are secured to the under side of the inclined plate 29, by rods 36, 37, which are, respectively, welded to said upper ends and to the under side of said inclined plate. The upper jaw also includes the stress receiving bar 38, which is made of highly carbonized steel, and is bevelled at the forward edge or side thereof, as at 39, Fig. 4, so that the surface of said edge

is in the same plane as the surface of inclined plate 29. Said bar 38 is rigidly secured to the forward side of table 26, by rods 40, 41, which are, respectively, welded to said table 26 and to said stress receiving member 38.

42 represents a pin or pivot which is rigidly secured in head 25; and extended into slot 43 in member 44, and said member 44 being rigidly secured to head 5, as by bolt 45, (see Figs. 3 and 4). 46, 46, represent rods which are welded to the heads 25, 25, and to the ends of the inclined plate 29, to join said heads to said inclined plates. The forward end of the upper jaw is movably connected to the lower jaw of the brake in the ordinary way, as by a link, 47, at each end of the brake, which is pivotally mounted on head 5, as by bolt 48, and is connected to the upper jaw by eccentric 49, which fits in a corresponding aperture in lever 50, said lever being pivotally mounted on head 25, as by bolt 51. The stress receiving member 38 is forced down onto a bar or sheet of metal placed on lower jaw member 7, as say, 52, Fig. 4, by turning lever 50, Fig. 3, in the direction indicated by the arrow 53. 54 represents a counterweight on rod 55, said rod being secured to the apron or bending leaf by inserting the lower end thereof in socket 56, in the ordinary way of counter-balancing the apron.

In the modified construction illustrated in Fig. 6, the plate 14^a, forming an element of the apron, is joined to the lower side or edge of the thrust receiving bar, 15^a, in relative position to obtain ledge or shoulder 14^b, on which the lower side or edge of plate 23, (when said plate is used), may rest when secured thereto as is indicated by broken lines in Fig. 4. The upper side, 22, of the thrust receiving bar is retained, as hereinbefore described, but at the rear of said side there is a wall, 22^a, which is in a plane parallel with the planes in which the front and rear surfaces of said bar are positioned; and the upper side or edge of plate 16 is secured to the inclined face of said bar which extends from the bottom edge of said wall 22^a, and corresponds with the inclined face 21 (Fig. 4), hereinbefore described, by rods 18^a and 19^a, which are welded to said inclined face and to said plate, respectively.

The bar 7^a, forming the lower member of the clamping jaw of the brake is provided at its forward edge or side, with face 20^a, which is substantially at right angles to the upper and under faces of said member 7^a, and with the inclined face 20^b, which corresponds substantially with inclined face 20 hereinbefore described. Bar 7^a is rigidly secured to bed 6 by rods 9, 9, which are welded to said bed and to said bar, respectively.

This modified construction is used in the

large sizes of the brake, which are subjected to exceptionally heavy strains.

I claim:

1. In a bending brake, a supporting frame, a bed rigidly secured on said frame, heads at the ends of said bed, said heads respectively extended to form a hinge member, rods welded to said bed and to said heads to rigidly join said heads to said ends of the bed, a bar on the forward side of said bed arranged to form the lower member of the clamping jaw of the brake, and rods welded to said bed and to said bar to rigidly join said bar and bed, in combination with an apron comprising additional heads respectively extended to obtain a hinge member arranged to be pivotally joined to said first named hinge member, a metal plate and a thrust receiving bar, and rods respectively welded to said additional heads, said plate and said bar, to rigidly join said heads, plate and bar.

2. In a bending brake, a supporting frame, a bed rigidly secured on said frame, heads at the ends of said bed, said heads respectively extended to form a hinge member, rods welded to said bed and to said heads to rigidly join said heads to said ends of the bed, a bar on the forward side of said bed arranged to form the lower member of the clamping jaw of the brake, said bar bevelled on the under side of the front edge thereof, and rods welded to said bed and to said bar to rigidly join said bar and bed, in combination with an apron comprising additional heads respectively extended to obtain a hinge member arranged to be pivotally joined to said first named hinge member, a metal plate and a thrust receiving bar, the front portion of the upper edge of said thrust receiving bar in a plane at a right angle to the sides thereof, and the rear portion of said upper edge bevelled to correspond with the bevel on said first named bar, and rods respectively welded to said additional heads, said plate and said thrust resisting bar, to rigidly join said heads, plate and bar.

3. In a bending brake, a supporting frame, a bed rigidly secured on said frame, heads at the ends of said bed, rods welded to said bed and to said heads, to rigidly join said heads to said ends of the bed, a bar on the forward side of said bed arranged to form the lower member of the clamping jaw of the brake, and rods welded to said bed and to said bar to rigidly join said bar and said bed, in combination with a movable upper member comprising heads, a horizontal metal plate, an inclined metal plate and a thrust resisting bar the forward edge whereof is bevelled in a plane substantially corre-

sponding with the plane of the upper side of said inclined plate, said bar arranged to form the upper member of the clamping 65 jaw of the brake, and rods welded to said plates, said heads, and said bar to rigidly join said plates, bar and heads.

4. In a bending brake, the combination of a supporting frame, a bed rigidly secured 70 to said frame, heads at the ends of said bed, a bar on the forward side of said bed arranged to form the lower member of the clamping jaw of said brake, and rods welded to said bed, said heads and said bar, respectively, said heads extended to form a hinge member, an apron comprising heads respectively extended to form a hinge member to co-act with said first named hinge member, a plate and a thrust resisting bar, and rods 80 welded to said last named heads, said plate and said thrust resisting bar, and a movable upper member also comprising heads, a substantially horizontal plate, an inclined plate and a thrust resisting bar the forward edge 85 whereof is bevelled to substantially correspond with the plane of the upper face of said inclined plate and arranged to form the upper member of the clamping jaw of the brake, and rods welded to said last 90 named heads, said plates and said bar.

5. In a bending brake, the combination of a supporting frame, a bed rigidly secured on said frame, heads at the ends of said bed, a bar on the forward side of said bed arranged to form the lower member of the clamping jaw of said brake, and rods welded to said bed, said heads and said bar, respectively, said heads extended to respectively form a hinge member, an apron comprising heads respectively extended to form a hinge member to co-act with said first named hinge member and pivotally attached thereto, a plate and a thrust resisting bar, and rods welded to said last named heads, 100 said plate and said thrust resisting bar, said bar forming the lower member of the jaw of the brake and said thrust resisting bar correspondingly bevelled on adjacent edges thereof, and a movable upper member also 105 comprising heads, a substantially horizontal plate, an inclined plate and a thrust resisting bar, the forward edge whereof is bevelled to substantially correspond with the plane of the upper face of said inclined plate, said bar arranged to form the upper member of the clamping jaw of the brake, and rods welded to said last named head, 110 said plates and said bar.

THOMAS J. KELLEHER.

In the presence of—

W. H. DREIS,
A. H. BRAINARD.
